UNITED STATES PATENT OFFICE

THOMAS KARLOVITCH AND JOHN SEBES, OF MOUNT CARMEL, PENNSYLVANIA

CLASSIFYING APPARATUS

Application filed July 5, 1929. Serial No. 376,133.

Our invention relates to apparatus of the type known as classifiers, which is employed in the operation of classifying and separating from a mixture of substances those of different specific gravity.

Specifically our invention relates to an apparatus commonly known as a coal jig, which is employed for the cleaning of coal and the separating of the coal from slate, stone, and the like, which may be intermingled therewith. This is possible of accomplishment by means of a coal jig wherein water is employed, because the coal is of a lower specific gravity than the slate, stone, and the like which may be intermingled therewith.

The general object of our invention is to provide an apparatus embodying novel features of construction the presence of which enables a more efficient and complete separation of the slate, stone and the like which may be intermingled with the coal than heretofore has been practical.

It also is an object of our invention to provide a classifying apparatus for the treatment of a mixture of coal and impurities (such as slate, stone and the like), comprising novel means whereby a bed of slate, stone and the like of uniform depth throughout its width is maintained at all times during the operation of the apparatus, so that separation of the coal from the slate and stone is efficiently and completely effected.

A further object of our invention is to provide a construction of apparatus for the cleaning of coal, provided with means of novel construction whereby the slate gate is prevented from becoming locked against opening and closing movement, the result being that the efficiency of the apparatus is enhanced to a substantial degree.

To the foregoing and other ends to which reference will or may be made hereinafter the invention comprehends the different forms of apparatus as illustrated in the drawings and as covered by the claims.

In order that the invention may be readily understood and its practical advantages fully appreciated reference should be made to the drawings, wherein,—

Fig. 1 is a view in longitudinal sectional elevation of one form of construction of classifier embodying the invention;

Fig. 2 is a view in top plan thereof;

Fig. 3 is an enlarged vertical longitudinal view in sectional elevation of the jig pan and certain associated parts shown in Figs. 1 and 2;

Fig. 4 is a top plan view of the jig pan shown in Fig. 1;

Fig. 5 is a view in elevation of the discharge end of the jig pan;

Fig. 6 is a vertical sectional view taken along the line 6—6 of Figs. 4 and 5;

Fig. 7 is a top plan view showing a modified construction of jig pan embodying the invention;

Fig. 8 is a longitudinal sectional view taken on the line 8—8 of Fig. 7;

Fig. 9 is a view in elevation of the discharge end of the jig pan shown in Figs. 7 and 8;

Fig. 10 is a view in top plan showing another modified construction of jig pan;

Fig. 11 is a longitudinal sectional view of the discharge end portion of the jig pan taken on the line 11—11 of Fig. 10; and

Fig. 12 is a view in elevation of the discharge end of the jig pan shown in Figs. 10 and 11.

In the drawings we have shown a classifying apparatus comprising a tank 1 which is adapted to contain water. This tank is of usual construction and need not be described in detail. A jig pan 2 having a perforated bottom 3 is suspended by means of supporting bars 4 from eccentric straps 5 which in turn are supported upon eccentrics 6 mounted upon a shaft 7. The supporting bars 4 are secured to the opposite sides of the jig pan 2 and extend below the same. The lower ends 80

thereof terminate in reduced portions 10 which extend through openings provided in inwardly extending flanges 11 of brackets 12 mounted upon the sides of the tank 1. In the 5 operation of the machine eccentrics 6 cause lateral movements of the upper portions of the supporting bars 4 and also cause vertical movements thereof, the lower reduced end portions 10 sliding up and down in the openings in the flanges 11 to permit such vertical movements. Such movements of the supporting bars 4 impart to the jig pan 2 corresponding rocking and vibratory movements. The shaft 7 with the eccentrics 6 thereon is 10 rotated by means of power applied thereto through a belt 13 driven by means not shown. A driving pulley 15 is mounted upon the shaft 7 which drives a belt 16 to drive rollers or shafts (not shown) for actuating the endless conveyors 17 and 18 by means of which the coal and slate are conveyed from the separate compartments within the tank 1 into which they are delivered, respectively, from the jig pan 2. The mixture of coal and impurities to be treated is delivered into the 15 jig pan 2 at the point 20 and passes underneath the adjustable baffle plate 21 and thence toward the rear or discharge end of the jig pan under the influence of the rocking vibratory movements imparted to the jig pan by the action of the eccentrics 6 and the supporting bars 4 the lower ends of which are guided in their vertical movements by the 20 openings in the flanges 11. The impurities referred to may consist of slate, stone and the like and have a higher specific gravity than the coal, whereby the said impurities collect upon the bottom of the jig pan to form a bed thereon, while the coal is buoyed upwardly 25 and caused to rise above the bed and to be discharged over the upper edge portion of the breast plate 25 which is located at and extends transversely of the discharge end of the jig pan, the area of which is reduced and is 30 considerably smaller than the transverse area of the main body portion of the jig pan. In the construction as illustrated the rear end portion of the upper wall of the jig pan (having reference to Figs. 2 and 4 of the drawings) is inclined inwardly, as indicated at 26, so that the area of the rear end of the jig pan is substantially reduced. The coal, as a result of being buoyed upwardly by the action thereon of the water in the tank 1, passes over 35 the upper edge of the breast plate 25 and enters the upper end of the chute 27 and is discharged from the latter into a compartment within the tank 1, from which it is removed by means of the endless belt or conveyor 17 (to which reference has been made previously).

For the purpose of permitting the impurities (including slate, stone and the like) to be discharged as necessary from the bottom 60 of the jig pan 2, we have provided a perfor-

ated slate gate 30 which is formed at its upper edge integrally with a bar-like member 31, the opposite ends of which are projected and form trunnions which are supported upon adjustable bearings 32 located in 70 pockets or openings 33 provided in the lower ends of brackets 34 which are secured upon the outer sides of the side walls of the jig pan 2. Adjustment of the bearings 32 is effected by means of the adjustable bolts 35 which have screw-threaded engagement with the lower ends of the brackets 34. The inner ends of the said bolts 35 project into the pockets 33 within which the bearing blocks 32 are 75 located. 80

Upon reference to Figs. 1 to 6 of the drawings it will be noted that the refuse gate 30, over which the slate, stone and the like are discharged, is of a shape corresponding to that of the horizontal area of the rear or discharge end portion of the jig pan. The lower edge of the gate 30 (having reference to Figs. 2 and 4 of the drawings) extends in a line parallel with the side of the main body portion of the jig, whereas the opposite or upper edge 26 is inclined inwardly and extends at an angle to the length of the said jig pan, as is indicated at 40. As already suggested, the gate 30 is pivotally mounted, the axis of its pivotal movement being the axis of the member 31. At the opposite corners of its rear end the gate 30 is provided with arms 41 which project rearwardly therefrom and are pivotally connected to the lower ends of supporting links 42, the upper ends of which are pivotally connected to arms 43 which project rearwardly from a rock shaft 44 supported at its opposite ends in bearings 45 provided upon the upper ends of brackets 46 mounted upon the upper edge portions of the opposite 90 side walls of the jig pan 2. An arm 47 is rigidly connected at one end to the rock shaft 44 and extends toward the front of the apparatus over the jig pan 2. The said arm is provided with a weight 48 which is adjustable thereon. By varying the position of the weight 48 upon the arm 47 the lifting force applied to the gate 30, tending to hold it in its uppermost position against the lower edge of the breast plate 25, is varied. The 95 force applied by the weight 48 to hold the gate 30 in its uppermost position operates to control the discharge of impurities from the said gate and thereby to control the thickness of the bed of impurities (including slate, stone and the like) upon the said gate and upon the bottom 3 of the jig pan. The weight of the impurities which gather upon the gate 30 constitutes a force due to gravity which acts against the force due to the weight 48 upon the arm 47 and tends to open 100 the gate 30. The amount of resistance offered by the weight 48 to such opening will control the thickness of the bed of impurities upon the said gate 30 and upon the bottom 105 110 115 120 125 130

tom 3 of the jig pan. It will be apparent, therefore, that by adjustment of the weight 48 upon the arm 47 the thickness of the bed of impurities upon the gate may be controlled and regulated.

It will be noted that the gate 30 is of the same shape as the horizontal cross-sectional area of the rear or discharge end portion of the jig pan 2, and that its opposite edges are located within and in adjoining relation to the oppositely disposed portions of the side walls of the said jig pan, one of the said portions being the inclined portion 26. It also will be noted that the length of the upper edge portion of the breast plate 25 is equal substantially to the width of the discharge end of the jig pan and to the rear end portion of the gate 30. By reason of the fact that the discharge gate 30 is tapered toward its rear end, so that its rear end is of the same width as the discharge opening through which the coal is discharged from the jig pan, and that both are tapered, the maintaining of a bed of impurities of uniform thickness throughout the width of the rear end portion of the jig pan structure is rendered practically possible. It will be found that in the operation of an apparatus embodying the invention a bed of slate, stone and the like may be maintained at the desired or predetermined thickness upon the gate and upon the bottom of the jig pan at all times and that the coal will be discharged at all points along the upper edge of the breast plate 25 and that there will be no "dead points" where the coal will come to rest.

It will be noted that the opposite edges of the gate 30 are located inside of the lower edge portions of the opposite sides of the rear end section of the jig pan. In order that the edge of the gate 30, which is located in proximity to the inner side of the inclined end portion 26 of the jig pan, may be maintained at all times during its pivotal movements in proper position with respect to the said inclined side we have bent or inclined the lower edge of the latter inwardly, as indicated at 50. The inner surface of the inwardly inclined portion 50 may be curved so that the different vertically extending elements of which the surface may be composed are concentric with the axis of the member 31. When so curved the edge of the gate 30 in proximity thereto will maintain the same position or relation with respect to the same at all times during its pivotal movements; but in practice the inner surface of the inwardly extending portion 50 may be plane, as illustrated. By locating the opposite edges of the gate 30 inside of the opposite side walls of the rear end portion of the jig pan 2 there is no possibility of the gate becoming locked against movement by the gathering of impurities or other material between the edges

of the said gate and other portions of the structure. In other words, the structure embodying our invention is of a character such that the gate 30 is always free to operate under the influence of the weight of the impurities which gather thereon and of the weight 48 upon the arm 47.

Although in the construction illustrated in Figs. 1 to 6 inclusive, we have inclined or tapered the rear end portion of the upper wall of the jig pan, it will be understood that such wall may be straight and that the rear end portion of the lower wall may be bent inwardly and that the lower edge of the gate 30 may be inclined inwardly, the construction being exactly the reverse of that which is shown.

Instead of providing a tapered outlet for the coal and for the impurities (including slate, stone and the like) by inclining the rear portion of one of the side walls of the jig pan and the adjoining edge of the gate 30 the rear end portions of both side walls may be inclined, as indicated at 60 in Figs. 7 to 9 inclusive, of the drawings, in which event the opposite edges of the discharge gate 61 may be inclined or tapered, as indicated at 62. In the construction as illustrated in these Figs. 7 to 9 inclusive, the lower edges of both of the converging side wall portions 60 are bent inwardly, as indicated at 63, for the same purpose as has been described with respect to the inwardly bent portion 50 of the construction shown in Figs. 1 to 6 inclusive. The remaining portions of the structure disclosed in Figs. 7 to 9 inclusive, are substantially identical with the corresponding parts or portions of the construction shown in Figs. 1 to 6 inclusive, and need not be referred to again. The operation of the structure shown in Figs. 7 to 9 inclusive, is identical with that of Figs. 1 to 6, inclusive.

In the construction as illustrated in Figs. 10 to 12, inclusive, the side walls are continued to their rear ends in straight lines, as indicated at 65, and the discharge gate 66 is of rectangular shape, as shown, its opposite edges being located within and in adjoining relation to the inner sides of the rear end portions 65 of the side walls of the jig pan. The opposite rear end portions 65 of the side walls of the jig pan being parallel with each other, as shown, and not converging toward each other as in the forms of construction shown in the previous figures of the drawings, it is not necessary that the lower edges thereof be bent inwardly, as described with respect to the corresponding portions of the previous structures.

The operation of the gate 66 is controlled in the same manner as in the construction illustrated in Figs. 1 to 6, inclusive.

It will be noted that in the several forms of construction the lower edges of the rear

end portions of the side walls of the jig pan are extended downwardly a considerable distance below the position occupied by the discharge gates when the latter occupy positions against the lower edge of the breast plate 25. The presence of these extensions insures that the opposite edge portions of the discharge gates will be located within and in adjoining relation to the rear end portions of the side walls of the jig pan at all times during operation.

It will be apparent that in the several forms of construction the relation of the opposite edges of the discharge gates to other portions of the jig pan structure is such that the wedging in of material between the gates and adjoining portions of the structure to prevent closing movements thereof is not possible practically. Hence the continuity of the operation is not likely to be interrupted.

By the employment of our invention we are enabled to produce or build a classifying apparatus adapted for use in the washing and cleaning of coal to effect the separation therefrom of impurities (such as slate, coal and the like) which apparatus includes means whereby a bed of refuse upon the bottom of the jig pan and upon the discharge gate will be of uniform depth throughout the width of the pan, and whereby also the coal will be discharged continuously throughout the width of the discharge opening at the rear or discharge end of the jig pan structure. For these reasons a classifying apparatus embodying our invention is highly efficient.

Having thus described our invention what we claim and desire to secure by Letters Patent is:

1. A classifying apparatus of the character described, comprising a jig pan having the rear end portion of a side wall thereof bent and extended in a direction transversely of the length of the said pan, the lower edge of the said inwardly extended portion being projected beyond the plane of the bottom of the said jig pan, the said extended portion being bent inwardly, a discharge gate located between the opposite side walls of the rear end portion of the said jig pan with its opposite side edges located in adjoining relation to the said portions, and means for pivotally supporting the said gate at its front end, permitting the rear end thereof to swing back and forth between the rear ends of the side walls.

2. A classifying apparatus of the character described, comprising a jig pan having opposite side walls the rear end portions of which extend in convergent relation to each other, the lower edges of the convergently related portions extending below the lower edges of the remaining portions of the side walls and one at least of the said extended

edges being bent inwardly, and a tapered discharge gate pivotally supported with its opposite edges located within and in adjoining relation to the rear convergently related side wall portions.

3. A classifying apparatus of the character described, comprising a jig pan having opposite side walls the rear end portions of which are bent and extended inwardly so that they are convergently related to each other, the lower edge portions of the said rear end portions being bent and extended inwardly, a discharge gate located between the said convergently related rear end portions of the side walls and having its opposite edges located in contiguous relation to the said portions, said edges being convergently related, means located at the rear end of the said gate for pivotally supporting the same, and means tending to hold the rear swinging end portion of the said gate in its uppermost position.

4. A classifying apparatus of the character described, comprising a jig pan having a relatively stationary perforated bottom and also having oppositely disposed side walls, the rear end portions of which are bent and extended inwardly and rearwardly and terminating in positions spaced a substantial distance from each other, the lower edges of said inwardly bent portions being bent and extended inwardly and downwardly, a tapered discharge gate, means located at the front end of said discharge gate for supporting the same with its front end in adjoining relation to the rear end of the said perforated bottom, a breast plate located in adjoining relation to the rear open end of the said jig pan, and means tending to hold the rear end of the said gate in its uppermost position in contact with the lower edge of the said breast plate and in a plane including the lines of the bends between the inwardly and downwardly extending bent lower edge portions of the rear end portions of the side walls and the vertically disposed parts of the said rear end portions.

5. A classifying apparatus of the character described, comprising a jig pan having a relatively stationary bottom and opposite side walls and rear end portions of which extend in convergent relation to each other, the lower edges of the convergently related portions extending below the plane of the said relatively stationary bottom and one at least of the said extended edges being bent inwardly, and a discharge gate, the opposite edges of which are convergently related, said gate being pivotally supported at its front end with its opposite edges located within and in adjoining relation to the rear convergently related side wall portions.

6. A classifying apparatus of the character described, comprising a jig pan having a relatively stationary bottom and opposite

side walls the rear end portions of which extend a substantial distance beyond the rear end of the said relatively stationary bottom, a discharge gate, pivotal means for supporting the front end of the said discharge gate, means for vertically adjusting the said pivotal means, and means for yieldingly supporting the rear end of said discharge gate, the opposite edges of the said gate being located within and in adjoining relation to the rear end portions of the opposite sides of said jig pan.

In testimony that we claim the foregoing as our invention we have hereunto signed our names this 28 day of June, A. D. 1929.

THOS. KARLOVITCH.
JOHN SEBES.
